UNITED STATES PATENT OFFICE.

FRANK G. LAYHER, OF JACKSON, MICHIGAN

AUTOMATIC ELECTRIC CROSSING-GATE.

No. 884,325.

Specification of Letters Patent.

Patented April 14, 1908.

Application filed November 27, 1906. Serial No. 289,278.

To all whom it may concern:

Be it known that I, FRANK G. LAYHER, a citizen of the United States, residing at Jackson, in the county of Jackson, in the State of Michigan, have invented a useful Improvement in an Automatic Electric Crossing-Gate, of which the following is a specification.

This invention relates to a gate for rail-way crossings and to means for automatically raising and lowering the gate; the gate being lowered as the train approaches the crossing and raised after the train has passed over the crossing.

The invention consists of a gate mounted upon a shaft, which shaft is turned through a quarter of a revolution by means of an electric motor; of an electric circuit including the motor and the track rails; of contact plates arranged adjacent to one rail and upon opposite sides of the crossing and adapted to be engaged by flanges of the engine wheels; and of a system of switches and relays included in the circuit whereby the motor is reversed so that the gate will be alternately lowered and raised.

In the accompanying drawings: Figure 1 is a diagrammatic view showing the circuits, motor, switches and relays. Fig. 2 is an end view of the gate and other mechanism for operating the gate; a casing being shown in section. Fig. 3 is a side view, the gate being partially broken out, the casing being shown in full lines, and the relays being shown diagrammatically. Fig. 4 is a front face view of certain switches and contact plates. Fig. 5 is a vertical section through the switch board, the switches being shown in elevation. Fig. 6 is a detail perspective view of certain circuit breaking and making means. Fig. 7 is an end elevation of parts shown in perspective in Fig. 6.

In these drawings A, B, C and D represent relays of the usual kind and A' represents a double armature arranged between the poles of the relays A and B and carrying a contact plate B' provided with suitable contact points. Curved contact plates E are placed upon a suitable base, as for example, upon a piece of slate E' and upon the same base are arranged concentric contact plates E', the ends of which overlap the contact plates or strips E.

1 represents the gate, which may be of any desired construction and which is mounted upon a shaft 2, which shaft is journaled in a

suitable casing 3. The shaft M is also journaled in the casing but passes loosely through the base E' and carries oppositely extending switches E' which are secured at their inner ends in a suitable collar E' which is rigidly secured upon the shaft M and which is of any desirable insulating material or which is insulated from the shaft M.

The outer end portion of each switch E' slides upon the contact strips E and E' arranged upon the said side of the collar E'. A suitable motor F is arranged in the casing and is provided with an armature F' and field coils F'. A suitable gear train G transmits rotary motion from the shaft of the armature F' to the shaft 2 upon which the gate is mounted. A gear wheel G' is fixed upon the shaft 2 and meshes with the gear wheel M' of the same diameter and fixed upon the shaft 75 M whereby a movement of 90° of the shaft 2 will impart a quarter revolution to the gate to shaft M and to switches E'.

To connect the motor in circuit and cause the gate to be moved in the proper direction and at the proper time, the following arrangement of the batteries and conductor wires is employed: Adjacent one side of the track 4, the rails of which form a part of the circuit, are placed contact points 5 upon opposite sides of the crossing barred by the gate. These contact points may be any desired distance from the crossing and are connected by a wire 6, which extends parallel to the track. The wire 6 is tapped, at the casing 3, by a wire 7 which extends to the relay A. A wire 8 leads from the relay A to a battery H and from the battery H to the track rail upon the side opposite the contact points 5.

The various circuits will be more clearly understood by describing them in combination with the operation of the device: Assuming that the gate is in its normal or upright position, a train approaching the crossing from either direction will bring a flange of one of the drive wheels of the engine in contact with one of the contact plates 5, and it will be obvious that these plates may be of any desired length. The axle will serve as a conductor connecting the rails 4 and a circuit will be formed through the wire 7, relay A and wire 8, and the relay A will be energized from the battery H and will attract the armature A', which attraction will bring the contact plates B' into engagement with contact points B' and a circuit will be formed

22

through a wire 9 leading from one of the contact points B^3 to the relay D by way of a wire 10 which taps the wire 9, and from the relay D through a wire 11, through contact points 12 to a wire 13 to one of the contact strips E along the switch E^3 , through a slight contact with the said strip E, and through a wire 14 to the armature F' of the motor F, into a wire 15 to the other switch E^3 and thence to the curved contact strip E' with which the said switch E^3 is in engagement, and thence through a wire 16 to contact points 17 and through a wire 18 to a wire 19, which extends to the other contact point B^2 and in which a suitable battery J is inserted.

The field coils F^2 are energized in the following manner: The passage of current through the relay D causes it to attract an armature D' and the movement of this armature closes contact points 20, which points are arranged in pairs one point of each pair being carried by the armature. The circuit is therefore completed from the wire 11, which is connected to one of the said contact points 25 through the wire 21, the field coils F^2 and the wire 19 to the battery J. The motor being thus set in motion the shaft 2 is rotated by the gear train G and the gate is lowered. The rotation of the shaft 2 is transmitted by 30 the gears G' and M' to the shaft M and the switch arms E' are moved over the curved strips E and E' into approximately the position shown by the dotted lines in Fig. 1. Before this movement is completed the switch arms E' will have passed from and broken contact with the contact strips upon which they rest when the turning movement commences, and will be in engagement with the other concentrically arranged strips. 35 This movement of the switch arms will automatically cut out the armature F' as soon as the switch arms have broken contact with the strips with which they originally engaged, and the further movement of the switch arms will be due to the momentum 40 acquired by the motor and gate, which momentum will carry the switch arms into substantially the position shown by the dotted lines in Fig. 1. The gate will now be in its 45 lowered position and after the train has passed the crossing, it will come into contact with the other contact plate 5 and a circuit will be established through the relay A in the same manner as at first.

50 To deenergize the relay A after the gate has reached the lowered position and restore the armature A' to the position shown in Fig. 1, certain means are employed which will be described hereafter. On the re-com-55 pletion of a circuit through the relay A and passage of the engine from the second contact plate 5, the armature A' will be again attracted by the relay A and the contact plates B' will again make contact at the 60 points B^2 . A circuit will be established

through the wires 9, the relay C, wire 24, contact points 25, wire 26, one of the strips E, switch arm E^3 , the wire 15, armature F', the wire 14, the other switch arm E^3 , strip E', wire 27, contact points 28, the wire 29, wire 18, and wire 19 through the battery J to the other point B^2 . It will thus be obvious that the current will pass through the motor armature in the opposite direction and the reversal of the motor will serve to raise the gates in the same manner in which they were lowered.

To energize the field coils F^2 for the reversal of the motor F, current is passed through the same points through the following circuit. The energizing of relay C attracts its armature C' and this armature carries contact points 30, similar to the contact points 20 carried by the armature D'. A circuit is therefore completed from the wire 24 through the contact points 30 and through the wire 21 to the field coils F^2 and back through the wire 19 to the battery J. It will be noted that the contact points 12 and 17 are carried by the armature C' and are broken when the armature is attracted and contact is made at the point 30. That the contact points 25 and 28 are carried by the armature D' and are broken when the contact is made at the points 20.

To cut out the relay A when the gate has reached the limit of its travel in either direction, any suitable tripping mechanism may be employed in connection with a circuit breaking device, and in the drawings, I have illustrated a form consisting of an outwardly extending arm E^4 , on the base E^4 , upon which is secured a depending spring O, suitably insulated from the arm E^4 . The base E^4 carries a contact point 32 which is adapted to be engaged by a contact 33 carried by the spring O. On the shaft M are rigidly secured two radial arms N and N' which carry compound curved contact arms 34 and 35 at their free ends, the said arms being oppositely arranged. The action of these arms is clearly shown in Fig. 6 and also their relative arrangement with respect to each other. As the arm 34 passes between the contacts 32 and 33 they will be held apart and prevented from, in any manner, accidentally coming into contact. As the arm 35 passes the contact points, it will pass upon the outer side of the spring O, and the curved portion of the arm 35 will force the spring O inwardly and bring the contact points 32 and 33 into engagement, these points being in circuit with the wires 23 and 31.

It will be obvious from the above description that when a train approaches the crossing and the engine reaches the first contact plate 5, the motor will be set in operation in one direction and the gate or gates will be lowered, the motor being automatically cut out as the gate approaches the horizontal

position. After the train has passed the crossing and when it reaches the second contact plate A⁵ the motor will be again automatically brought into the circuit and will be driven in a direction reverse to its former rotation and the gate will be elevated, the motor being again cut out automatically as the gate approaches an upright position.

It will be obvious that the gate will be lowered by a train approaching from either direction and raised after a train has departed in either direction.

It will be also obvious that a duplicate gate can be arranged so that a gate will be upon each side of the track, the second gate being operated from the shaft 2, by means of a suitable sprocket chain P, and shaft Q, but the number of gates or the particular construction of the gate is not material to this invention.

Having thus fully described my invention what I claim as new and desire to secure by Letters Patent is:—

1. A device of the kind described comprising a vertically movable gate, a motor to operate the gate, contact plates in the path of an engine on opposite sides of the gate, relays, a double armature between poles of adjacent relays, a base, curved contact strips on said base, concentrically arranged contact strips overlapping the first mentioned strips, a shaft, switch arms carried by the shaft oppositely arranged and movable on the contact strips, means for rotating the

shaft in unison with the gate, and electrical circuits including the relays, switches, contact plates and motor.

2. In a device of the kind described, the combination with a relay, of an electrical circuit including said relay, a base, an arm carried by the base, a spring carried by the arm, there being contact points on the base and spring, a rotatable shaft, radial arms carried by the shaft, and curved arms at the ends of the radial arms, said curved arms respectively forcing the contact points of the base and spring into and out of contact with each other.

3. In a system for electrically operating crossing gates a track portion forming a portion of a circuit, said circuit being completed by entrance of a train on said track portion, a relay in said circuit, an armature co-acting with said relay and adapted when attracted to close a second circuit, a second relay, a motor, a reversing switch, said relay, motor and switch being in the second circuit, a field coil circuit closed by the energizing of the second relay, means for automatically breaking the said circuits, and means for completing a third circuit and passing the current through the motor in the opposite direction as the train leaves the track portion.
